CENTRIFUGE APPARATUS AND ROTOR THEREFOR

Edward G. Pickels, Atherton, Richard C. Stallman, San Carlos, and Philip F. Scofield, Atherton, Calif., assignors to Beckman Instruments, Inc., Fullerton, Calif., a corporation of California

Application December 28, 1956, Serial No. 631,163

8 Claims. (Cl. 233—11)

This invention relates generally to a centrifuge apparatus and rotor therefor and more particularly to a high speed centrifuge apparatus of the above character in which the temperature of the rotor is maintained near the outside temperature.

It is a general object of the present invention to provide a centrifuge apparatus in which the rotor is maintained at a temperature near that of the outside air by insulating the outer periphery of the rotor and circulating outside air through the center of the rotor.

It is another object of the present invention to provide an ultracentrifuge in which means are carried by the rotor for circulating outside air through the rotor and the rotor chamber.

It is a further object of the present invention to provide an ultracentrifuge apparatus in which the rotor has a relatively small axial opening through which outside air is circulated to effect a heat exchange with the rotor and maintain the same at a temperature near that of the outside air.

It is another object of the present invention to provide an ultracentrifuge apparatus in which the rotor has an axial opening and means is mounted on the bottom of the same which serves to circulate outside air through and about the rotor to maintain the same at a temperature near that of the outside air.

It is a further object of the present invention to provide an ultracentrifuge rotor which includes a relatively small axial hole formed therethrough having cooling fins and a centrifugal pump mounted on the bottom of the rotor and serving to circulate outside air through the opening, and in which the external surfaces of the rotor are covered with insulating material whereby conduction of heat, generated by the friction of the surrounding air against the external surfaces of the rotor, into the body of the rotor is reduced by the insulating layer.

These and other objects of the invention will become more clearly apparent from the following description taken in conjunction with the accompanying drawing.

Referring to the drawing:

Figure 1 is a perspective view showing an ultracentrifuge incorporating the present invention;

Figure 2 is a plan view partly in section of the apparatus of Figure 1;

Figure 3 is a sectional view taken along the line 3—3 of Figure 2;

Figure 4 is an enlarged plan view of a typical rotor;

Figure 5 is a sectional view taken along the line 5—5 of Figure 4; and

Figure 6 is a sectional view taken along the line 6—6 of Figure 5.

The centrifuge apparatus illustrated in the drawing comprises an outer housing 11 which serves to house the working parts. The controls are mounted on the front panel of the housing. They include the cover release knob 12, the circuit breaker reset knob 13, the start and stop switch 14 and a timer control 16.

The top of the housing is provided with an opening

2

17 through which the rotor may be installed and removed. A sliding door 18 serves to cover the hole. The door 18 is formed with an opening, preferably louvered, as will be presently described, through which air may circulate. The covered box 19 provides means for storing speed change gears and belts.

Referring particularly to Figure 3, the door or panel has an opening 20 directly over the rotor. The opening is provided with a plurality of louvers 21 through which the air circulates, as indicated by the arrows 22. The opening is preferably of restricted size whereby most of the air which circulates downwardly through the same, as will be presently described, is directed downwardly through the center of the rotor. The door has spaced rollers 23 mounted on each edge thereof. The rollers ride in the guiding channel 24 secured to the sides of the housing. A latch mechanism (not shown) works in conjunction with the release knob 12 to release the panel to provide access to the rotor chamber.

The rotor is operated within the cylindrical chamber 26 which acts as a guard in the event of breaking or explosion of the rotor under the strains occasioned at the high operating speeds at which it operates. Similarly, the louvers are so formed that if such breakage should occur, none of the parts will fly out through the top and damage surrounding equipment or injure personnel.

The cylindrical chamber 26 is mounted on the base 27 by a plurality of pins 28 which are suitably secured to the bottom thereof, as for example by forming a hole in the bottom and threading the same as indicated at 29. The pins serve to hold the bottom edge of the cylinder 26 above the base 27, whereby air may circulate out through the opening formed between the base and cylinder. Thus, the air circulates downward through the door, through the rotor and outward through the space formed between the bottom edge of the cylinder 26 and the base 27 as indicated by the arrows 31.

The rotor 32, to be presently described in detail, is mounted on the end of the flexible shaft 33. The bottom end of the shaft 33 is tapered (Figure 5) and is adapted to fit into the taper formed in the shaft 34. The bearing 35 is mounted on the shaft 34 and is adapted to fit against the shoulder 36 formed in the housing 37. The snap-in washer 38 serves to retain the bearing against the shoulder 36. The bearing hub 39 is secured to the shaft 34 and is locked to the same by means of the screw 41. The lower end of the shaft 34 is drilled out to form the axial opening 42. The end portion rides in the bushing 44 and is provided with the spiral grooves 46 which communicate through the openings 47 with the inside of the housing. When the shaft 34 is being rotated at high speeds, the helical grooves serve to pump spindle oil from the chamber 48 downward. The oil then flows upwardly through the opening 42 and is forced through the openings 49. The stream or jet of oil strikes the bearing and serves to lubricate and cool the same. The upper portion of the chamber 37a is suitably secured to the lower portion 37b which includes the bushing by means of screws 53. An O-ring 54 serves to form a suitable seal. The plug 55 provides means for filling the chamber 48.

A gear 56 is mounted on the hub. The gear 56 is engaged by the belt 57 (Figure 3) which is driven by a suitable constant speed motor 58. The motor is mounted on the base 27 as, for example, by means of the bracket 59. To change speeds the plate 61 which is attached to the base 27 and which is accessible through the chamber is removed and the gear and belt replaced to give the suitable driving speed.

Referring now more particularly to Figures 4 and 5, a novel rotor is shown. The rotor comprises a metal block 66 of substantially frusto-conical form. The block

includes a plurality of cavities or wells 67 extending from the upper end of the block to a point adjacent the lower end. The axes of the wells are substantially parallel to the conical face of the block and converge in the direction of the axis of the rotor. A coating of insulating material 68 is formed on the outside of the block. The coating may, for example, be an epoxy plastic which is added by dipping the rotor in the liquid plastic. Prior to dipping the rotor in the epoxy solution it may be cleaned by dipping the same in a chromic acid bath.

A relatively small axial opening 69 is formed in the block and serves to accommodate the cooling fin structure designated generally by the reference numeral 71. The cooling fin structure includes an outer cylinder 72 and an inner member 73. A plurality of fins 74, which may be made from sheet copper or other like material, are formed in a zigzag pattern between the outer cylinder 72 and the inner surface 73 with the ends of the same suitably secured, as for example, by welding or soldering to the adjacent member. These fins serve to form cooling surfaces over which air may be circulated, as will be presently described, to cool the rotor. The inner member 73 supports the rotor and the drive assembly 76 through the fins 74 and is bored to accommodate the drive assembly 76 which is attached to the shaft 33 for example, by welding. The assembly 76 includes a cylindrical block 77 to which are attached pins 78. The pins 78 are adapted to ride into the openings 79 formed in the member 73. Thus, the outside edges of the cylindrical member 77 serve to hold the assembly coaxial with the inside opening formed in the member 73. The lower portion of the member 73 is threaded at 81 to receive the impeller 82. The impeller 82 includes a plurality of fins 83. The impeller acts as a centrifugal pump, pumping air downwardly past the fins and outwardly as indicated by the arrows 84 (Figure 3).

A lid or cover 86, preferably made of insulating material, is held over the top of the rotor by the nut 87 which is threaded at 88 to the rotor. The nut 87 is shaped to funnel the air into the opening 69.

In operation, the test tubes having the mixture to be separated are inserted into the wells. The rotor is then mounted on the end of the flexible shaft 33 and the apparatus is turned on. Since the apparatus operates at relatively high rotative speeds, a relatively long period of time is required for the apparatus to come up to speed. As the rotor comes up to speed, outside air is pumped down through the opening 20 by the action of the pump mounted on the rotor. Most of the air circulates down through the central opening in the rotor with a small fraction flowing down past the outside of the rotor. A small portion of the air is recirculated, but this is a minimum. The air flowing down through the rotor is at outside temperature and serves to rapidly bring the inside of the rotor to an equilibrium temperature near that of the air flowing through the same. Since the air flowing through the rotor flows in a portion of the rotor which is not moving at high velocity because the opening is relatively small, there is little frictional heating of the air travelling through the axial opening or the rotor. The rotor reaches its equilibrium temperature rapidly. As a result, convection effects which affect the separation of the mixture are greatly reduced and improved centrifugation results.

Ideally with the outside of the rotor perfectly insulated, the equilibrium temperature would be very near that of the outside air. However, for practical reasons, the outside rotor insulation cannot be made ideal. As a result, some of the frictional heat developed at the surface is conducted to the rotor. This heat is conducted into the center of the rotor and conveyed away by the air. The equilibrium temperature is slightly above that of the outside air.

Preferably, as previously described, the opening 20 is of restricted size whereby most of the air which flows

70

through the same flows through the rotor with very little spilling over the sides. This reduces the drag on the rotor and permits higher rotative speeds. This also serves to reduce the frictional heat generated at the outside surface of the rotor.

A rotor was constructed in accordance with the foregoing. The rotor was 5 inches long and was 4 1/4 inches in diameter at the top thereof and had 20 degrees of taper. 12 wells were formed in the block and were 10 equally spaced. The rotor had an insulating layer of epoxy-versamid 1/16 inch thick on the outer surface. The central opening 69 was 2 inches in diameter with the fin assembly having an inside member 1/8 inch in diameter and the outer cylindrical member 2 inches in diameter and 15 1/16 inch thick. The impeller was 2 1/2 inches in diameter and was provided with 6 blades.

The rotor was operated at rotative speeds of 24,500 r.p.m. and the temperature rise was found to be 4.5° C. above the outside air temperature of 23.0° C. For comparison, a standard rotor which was not insulated and in which air cooling means was not provided was tested. It operated at a temperature which was 13° C. above the outside air temperature with the same rotative speeds and air temperatures. The novel apparatus operates with greatly reduced temperature rise of the rotor.

Thus it is seen that an improved centrifuge apparatus and rotor have been provided. An insulating layer serves to reduce the conduction of heat generated between the rotor and the surrounding air. Means are provided for circulating outside air down through the center of the rotor.

We claim:

1. In a centrifuge apparatus, a chamber having an opening in the bottom region thereof, a cover having an opening formed therein and serving to close said chamber, a centrifuge rotor disposed in said chamber, said rotor having a relatively small axial opening formed therein a cooling fin assembly carried in said opening, means carried by said rotor for circulating outside air down through said cover and rotor opening past the fin assembly and outward through said bottom opening, said air serving to maintain the temperature of the rotor near that of the outside air.

2. Apparatus as in claim 1 wherein said means for circulating outside air through the cover and rotor comprises an impeller carried by the rotor and adapted to rotate with the rotor.

3. Apparatus as in claim 2 wherein the impeller is carried by the bottom of the rotor.

4. Apparatus as in claim 1 wherein a heat insulating coating is formed on the external surfaces of the rotor to reduce the conduction of frictional heat from the surface into the body of the rotor.

5. In a centrifuge apparatus, a chamber having an opening in the bottom region thereof, a cover having openings formed therein, a centrifuge rotor having a relatively small axial opening disposed in said chamber, a cooling fin assembly carried in said opening, a heat insulating coating formed on the periphery of said rotor and serving to reduce the conduction of heat from the surface into the body of the rotor, means for rotating said rotor, impeller means carried by said rotor and adapted to rotate therewith, to pump outside air downwardly through the cover, the axial opening of the rotor past the fins and out through the bottom opening to maintain the temperature of the rotor near that of the outside air.

6. A centrifuge apparatus comprising a chamber having an opening in the bottom region thereof, a cover having at least one opening serving to close said chamber, a centrifuge rotor comprising a frustro-conical block of material having a relatively small axial opening and a plurality of wells adapted to receive sample holders, a cooling fin assembly carried in said axial openings, an insulating cover for said rotor, means for securing the

cover to the rotor, means for driving said rotor, means carried within said axial opening for mounting the rotor on said driving means, an impeller carried at the lower end of said rotor, said impeller serving to circulate outside air downwardly through the rotor to maintain the temperature of the rotor near that of the circulating air.

7. A centrifuge apparatus as in claim 6 in which said frustro-conical block of material has an insulating coating formed on the surface thereof to reduce heat conduction from the surface into the body of the same.

8. A centrifuge apparatus as in claim 7 in which said chamber cover is movable to open and close the chamber, and in which the cover opening is louvered.
